CLAIM

The ornamental design for a battery connector, as shown and described.

DESCRIPTION

FIG. 1 is a perspective view of a battery connector, according to an embodiment of my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the battery connector that form no part of the claimed design.

The drawings include a separation and a bracket which represent a symbolic break in length of the battery connector. The appearance of any portion of the article between the break lines forms no part of the claimed design.
